MORTON L. JOHNSON, OF CHICAGO, ILLINOIS, ASSIGNOR, BY MESNE ASSIGNMENTS, TO
FRANK B. COOK COMPANY, OF CHICAGO, ILLINOIS, A CORPORATION OF ILLINOIS.

TELEPHONY.

1,173,774.

Specification of Letters Patent. Patented Feb. 29, 1916.

Application filed April 5, 1913. Serial No. 759,028.

To all whom it may concern:

Be it known that I, MORTON L. JOHNSON, citizen of the United States, residing at Chicago, in the county of Cook and State 5 of Illinois, have invented a certain new and useful Improvement in Telephony, of which the following is a full, clear, concise, and exact description, reference being had to the accompanying drawings, forming a part of 10 this specification.

My invention relates to telephone exchange systems of the class which employ prepayment or precharge equipment whose employment is prerequisite to the establishment 15 of connections between calling and called stations or which employ bookkeeping systems by which calling subscribers are precharged for definite periods of service and the invention has for its general object 20 the provision of an announcer to warn the subscribers, preferably both the calling and called subscribers, that the prepaid or precharged period of time is ended and the provision of a cutoff device for severing the 25 connection between calling and called subscribers at a suitable interval of grace after the announcer has furnished the warning.

The invention also contemplates means whereby either the operator or subscriber 30 may reset the announcer and cutoff devices again to operate in the event of an enlargement of the precharged or prepaid for period by a subscriber or operator.

I will explain my invention more fully by 35 reference to the accompanying drawings in which—

Figure 1 is a general diagrammatic view outlining the features of the invention and Figs. 2 and 3, taken collectively with the 40 lines at the lower right hand corner of Fig. 2 in alignment with continuations thereof at the left hand side of Fig. 3, illustrate the preferred embodiment of the invention in diagrammatic detail.

Like parts are indicated by similar characters of reference throughout the different figures.

Reference will first be made to Fig. 1 in which I have indicated two telephone stations 120 and 190 connected with spring jacks 1 at an exchange where link connectors 2 are employed for uniting the lines in conversation. As the invention is preferably embodied, a selector 3 is operated by called

subscribers when they remove their telephones from their switch hooks in response to the operation of their signal bells whereby a telephone repeater 4 and a talking device 5 are associated with the link 2 that connects the calling and called subscribers. The 60 talking device 5, then impresses telephonic current upon the line joining the stations whereby the called subscriber is asked the number of his line, the repeater 4 enabling the answer to this question to be telephonically impressed upon the line at the called station, the repeater permitting the telephonic current impressed at the called station to be conveyed to the telephone equipment at the calling station but preventing, 65 for the time being, telephonic current impressed at the calling station from reaching the called station. When the number of the called line has been given by the called subscriber the calling party will note that 70 it is in order for him to operate the pre-charge or prepayment device, and the operation of this device will complete the connection between the stations. The portion of the equipment including the elements 3, 75 4 and 5 is not essential in all embodiments of the invention but is useful where pre-payment or precharge equipment operated by calling subscribers is employed.

Whether the connection be established 80 between lines in the manner generally outlined or is otherwise established in a system where calling parties are precharged for periods of telephonic service which they desire, an announcer 6 is associated with an 85 established connection, after such connection is established between calling and called stations in both directions, this talking device being brought into telephonic association with the line joining the two subscribers at the termination of the pre-fixed period to warn the subscribers that such 90 period termination has been reached and that they are shortly to be disconnected. A cutoff device 7 is brought into play about a 95 quarter of a minute after the termination of such period to sever the connection between the stations, providing such period has not been extended, it being usual to allow this quarter of a minute of grace. The operator 100 is provided with a setting device 8 whereby she may delay the operation of the cutoff device 7 to any extent within the scope of

the system desired and will set the talking device 6 so as to operate at the termination of the extension of the period.

Referring now more particularly to Figs.

- 5 2 and 3, each of the substations may be provided with the usual telephone equipment comprising a telephone switch hook 9, a telephone receiver 10, a telephone transmitter 11, a call bell 12, and a condenser 13,
- 10 the switch hook having a normal contact for including the bell and condenser in bridge of this associate line and an alternate contact for including the telephone receiver and transmitter in another bridge of its associate telephone line. These telephone lines extend to the exchange where they terminate in jacks 1 which may be multiplied before various operators' positions.
- 15 In the embodiment of the invention illustrated station No. 120 is presumed to be the prepayment or precharge station and when such a station initiates a call a circuit is established which, in the embodiment of the invention illustrated, may be traced
- 20 from a grounded common battery 14, the line relay 15, the upper armature switch of the cutoff relay 16 and its normally engaged contact, both sides of the calling line and the telephone bridge uniting the same,
- 25 to the lower armature switch of the cutoff relay 16 and its normally engaged ground contact. The relay 15 will attract its armature switch to close circuit through the line signal lamp 17. The operator, in
- 30 response to this signal, will insert any plug 18 of a link connector 2 in the calling line jack 1, which may be the answering jack, appearing at her position whereupon a circuit is established that may be traced from
- 35 the grounded common battery 14, the relay 19, the heel of the answering plug 18, the thimble of the jack 1 engaging such heel, the cutoff relay 16, to ground whereupon the armature switches of this cutoff relay
- 40 are attracted to cut the line relay 15 and the signal lamp 17 out of circuit. The armature switch of relay 19 acts to close, upon the energization of relay 19, one gap in the circuit of a calling subscriber's supervisory lamp 20. The armature switch of the supervisory relay 21 in normal position serves to complete the circuit for the supervisory lamp 20 but this armature switch is attracted to open a circuit of said supervisory lamp when the telephone bridge is established at the calling station due to the establishment of a circuit for the relay 21 traceable from the grounded battery 14, the upper winding of a relay 22, the upper winding of relay 21, the tip of the answering plug 18, the tip spring of the engaged jack 1, both sides of the calling line and the telephone bridge uniting the same, the sleeve spring of the engaged jack 1, the sleeve of the plug 18, the lower winding of

supervisory relay 21, to the lower grounded winding of relay 22 which is equal but differential with respect to the upper winding of relay 22. The operator will depress her listening key 23 to bring her telephone set 24 in bridge of the link connector strands of the employed link connector 2 whereby the operator will be enabled to inquire of the calling station the number of the desired line, and when this number has been told to the operator she will insert the connecting plug 25 companion to the answering plug 18 in the jack 1 of the called line appearing at her position, assuming that such jack has tested idle, whereafter the operator will depress the ringing key 26 to bring the generator 27 in bridge of the called line to operate the signal bell 12 at the called station. The line relay 15 and signal 17 are excluded from circuit with the called line by the operation of the cutoff relay 16 so that when the called subscriber responds the signal 17 will not be displayed. After the ringing key 26 has been depressed a suitable interval it is released to connect 30 telephonically the plugs 18 and 25 to enable the called subscriber to effect the performance of certain functions which will now be described.

When the telephone receiver at the called station is removed in response to the operation of the signal bell thereat a circuit is established which is traceable from the grounded battery 14, the upper winding of the called supervisory relay 28, the upper strand of the employed link connector 2, the uppermost armature switch of relay 29 and its then engaged alternate contact (the relay 29 being included in the cutoff relay circuit established by the engagement of the heel of the connecting plug 25 and the thimble of the jack of the called line), the upper engaged pair of contacts of the ringing key 26, the tip of the connecting plug 25, the tip line spring of the jack of the called line, both sides of the called line and the telephone bridge uniting the same, the sleeve spring of the called line jack 1, the sleeve of the connecting plug 25, the lower engaged pair of contacts of the ringing key 26, to the lower grounded winding of the relay 28. The called subscriber's signal 30 is included in a circuit that has one gap closed by the middle armature switch of relay 29 when energized, the upper armature switch of relay 28, when this latter relay is energized, opening the circuit of the lamp 30 and closing the circuit of this lamp when the relay 28 is deenergized all as is well understood by those skilled in the art. The lowermost armature switch of the supervisory relay 28, when attracted, upon response of the called subscriber, establishes a circuit traceable from the lowermost grounded armature switch of relay 29, the alternate con-

tact of this relay, the actuated lower armature switch of relay 28 and its then engaged contact, the lowermost armature switch of relay 31 and its then engaged contact, the 5 relay 32, to the grounded battery 14. The relay 32 is now energized to cause the two uppermost armature switches to open the top talking strands of the employed link connector and the next two lower armature 10 switches to open the bottom talking strand of the employed link connector to prevent, at this stage of the operation, telephonic connection between the calling and called stations. The lowermost armature switch of 15 relay 32 now engages its alternate contact to establish a circuit traceable from the ground connected with this lowermost armature switch, said armature switch, the alternate contact thereof, the right hand armature 20 switch of relay 33 and its then engaged contact, the armature switch of relay 3 and its normal contact, the rotary magnet 35, the side switch wiper 36 in its first position, the interrupter 37 to the grounded battery 14. 25 The rotary magnet 35 now causes the step by step rotation of the wipers 37, 38, 39, 40, 41 and 42 until the wiper 41 engages an ungrounded waiting contact, the wiper 41 moving over a bank of waiting contacts each 30 individual to a relay 32 and its link connector 2, each relay 32 grounding its waiting contact in the presence of this switch 41 at the lowermost armature switch of relay 32 when engaging its normal contact. The 35 wipers 37, 38, 39, 40, 41 and 42 are each provided with waiting contacts individual to different link connectors and similarly positioned waiting contacts of different switches 3 are in multiple connection. When the 40 wiper 41 thus engages an ungrounded contact the circuit for the private magnet 43, which was closed upon the initial operation of the rotary magnet 35, is opened whereupon this private magnet causes the side 45 switch wipers 36, 44 and 45 to step to their second and final positions, the wiper 36 in its second position opening the circuit of the rotary magnet 35 to enable the wipers 37 and 42 to remain at rest. When the side switch 50 wiper 45 is in its second position it serves locally to establish a circuit for the relay 34 as will be apparent so that any other link connector 2 in which the relay 32 is energized will employ the next succeeding switch 55 3, since the armature switch of the relay 34 will transfer the connection from the rotary magnet 35 of the first switch 3 to the rotary magnet 35 of the next switch 3 as will be apparent. The side switch wiper 45, in its 60 second position, also establishes an apparent circuit for the relay 33 that is individual to the waiting contact now engaged by the wiper 42, this relay 33 being individual to the employed link connector 2. The relay 65 33 is employed to open the circuits that in-

clude the normal and alternate contacts of the lowermost armature switch of the associate relay 32 to prevent faulty operation.

When the switch 3 has been brought into association with the employed link connector 2, the repeater 4 and the talking device 5 are brought into service to enable the called party automatically to be asked the number of his line and to permit the called party to announce the number of his line to 70 the calling party but prevent the calling party from talking to the called party. The talking device 5 may be of the usual phonographic character having a talking record that may serve to say, for example, "What 75 is your number please", this query being spoken through a phonographic horn 46 that speaks in the telephone transmitter 47. This telephone transmitter is included in a closed local primary circuit having a primary or 80 inducing coil in secondary relation with an induced or secondary coil 48 included in a circuit that is traceable from one end of this coil 48 through a telephone receiver 49, condenser 50, the third from the top of the armature switches of relay 43 and the contact 85 then engaged thereby, the uppermost wiper 37, and the contact then engaged thereby, the uppermost armature switch of relay 32 and its alternate contact, the intermediate 90 armature switch of relay 51 and its then engaged contact, the uppermost armature switch of relay 29 and its alternate contact, the upper engaged pair of ringing key contacts of the key 26, the tip of the connecting 95 plug 25, both sides of the called line by way of the telephone bridge between these sides, the sleeve of the connecting plug, the lower engaged pair of ringing key contacts of the key 26, the lowermost armature switch of 100 relay 51 and its engaged contact, the next to the bottom armature switch of relay 32 and its alternate contact, the waiting contact engaged by the wiper 38, the armature switch immediately above the relay 43, and 105 its engaged contact, the condenser 52 to the coil 48. The called subscriber thus hears the question which is put by the talking device 5. The calling subscriber hears the same question which is telephonically impressed by the telephone receiver 49 upon the telephone transmitter 53 which is included in a closed local primary circuit having a primary winding in inducing relation to the secondary winding 54 that is included 110 in circuit with the calling line by a path traceable from the lower end of the winding 54, the uppermost armature switch of relay 43 and its engaged contact, the wiper 39 and its engaged contact, the next to the topmost armature switch of the relay 32 and its 115 engaged alternate contact, both sides of the calling line by way of the telephone bridge uniting the same, the armature switch immediately below the winding of relay 32 and 120 125 130

its alternate contact, the waiting contact engaged by the wiper 40, said wiper 40, the armature switch below the topmost armature switch of relay 43 and its engaged contact, 5 to the coil 54. The talking device 5 operates periodically to impress its speech and when not thus operating intervals are afforded within which the called station may answer the question, it being apparent that 10 voice currents impressed at the called station are impressed upon the receiver 49 and are consequently relayed to the telephone station by means of the transmitter 53 and the induced coil 54, this latter coil being included in circuit with the calling station by the path just traced. The calling subscriber cannot, at this stage of the operations, converse with the called subscriber because the transmitter 53 will not operate to 15 impress voice currents upon the receiver 49. When the calling subscriber has heard the response of the called subscriber to the query put by the talking device 5, the calling subscriber will, in some manner, prepay or 20 precharge himself with the desired connection to be used for a predetermined time. In the embodiment of the invention illustrated the calling subscriber prepays for the connection and for a predetermined period 25 during which such connection may continue, there being illustrated, by way of example, a coin receptacle 55 for receiving coins 56 which, during their passage to the receptacle, momentarily engage the contacts 57 30 momentarily to ground the calling line and thereby disturb the balance between the coils of the relay 22, the armature of this relay being thereupon momentarily attracted.

When the armature switch of relay 22 is 35 momentarily attracted it establishes a circuit traceable from this armature switch which is grounded, the contact of this armature switch, the intermediate armature switch of relay 31 and its normal follow up contact, the winding of this relay, to the 40 grounded battery 14. The relay 31 thereupon establishes a locking circuit for itself, which is necessary owing to the short duration of the circuit established at the armature switch of relay 22, which locking circuit is traceable from the grounded battery 14, the winding of relay 31, the intermediate armature switch of this relay, the alternate contact of this armature switch, the 45 lowermost armature switch of relay 29 and its alternate contact, to ground. The circuit of relay 32 is thereupon opened at the lowermost armature switch of relay 31, whereupon the four upper armature switches 50 of the relay 32 are released to engage their normal contacts and establish the telephonic continuity of the talking strands uniting the plugs 18 and 25 whereupon either subscriber 55 may impress telephonic current upon the telephone receiver of the other subscriber

during a period determined by the apparatus later to be described. The relay 56¹ is in parallel with the receiver 49 and was therefore included in bridge of the circuit telephonically uniting the called station with 60 the receiver 49, this relay 56¹ having been energized when the called subscriber responds for the purpose of establishing a circuit through the sluggishly operating relay 58, another circuit for this relay 58 65 having been previously established at the lowermost armature switch of the private magnet 43. The relay 56¹ is deenergized when its circuit is opened at the topmost switch and the next to the bottom switch of 70 the associate relay 32 and circuit for the relay 58 is thereupon opened at the released armature switch of the relay 56¹, the private magnet 43 having previously been deenergized, whereupon the released armature switch of the relay 58 establishes a circuit 75 traceable from this armature switch which is grounded, the contact then engaged by this armature switch, the previously closed off normal switch 59, the release magnet 60, 80 to the grounded battery 14, this release magnet operating upon the various wipers of the employed switch 3 in restoring them to normal.

As has been described, the relay 31 was 85 energized when the token 56 momentarily caused engagement between the contacts 57, the uppermost armature switch of the relay 31 then establishing a circuit traceable from ground through this armature switch, the contact of this armature switch, the uppermost armature switch of relay 51 and its 90 then engaged contact, the motor magnet 61, the interrupter 62, to the grounded battery 14. The motor magnet 61 will intermittently operate the ratchet wheel 62 that in turn will operate the gear wheel 63 whose shaft carries the wipers 64, 65. The wipers 64, 65 travel over banks of waiting contacts individual thereto and which banks of waiting contacts are connected with other banks of waiting contacts over which the wipers 66 and 67 are manually moved by the operator in unison. The interrupter 62 has a given 95 rate of operation and causes a given rate of travel of the wipers 64 and 65. It requires given intervals of time for the wipers 64, 65 to pass from contacts to contacts. For example, it may require a minute for each wiper 64, 65 to break engagement with one 100 waiting contact and enter engagement with a succeeding waiting contact. The wipers 66 and 67 are grounded and are set by the operator to determine which of the waiting contacts of the wipers 64, 65 are to be 105 grounded, the operator thereby determining the period during which the wipers 64 and 65 may travel before they encounter grounded waiting contacts.

It may be assumed that it takes the wiper 110

64 three minutes to move from normal to the first of its waiting contacts, four minutes to move to the second of its waiting contacts, and five minutes to the third of its waiting contacts and that it takes the wiper 65 three and one-quarter minutes to move from normal to the first of its waiting contacts, four and one-quarter minutes to move to the second of its waiting contacts and five and one-quarter minutes to move to the third of its waiting contacts, there being as many waiting contacts in each set as may be desired to suit the intervals during which it may be desired to preserve 15 connections between calling and called lines. Thus the wiper 64 encounters its waiting contacts a quarter of a minute in advance of the engagement of the wiper 65 with its waiting contacts and when the wiper 64 20 engages a waiting contact, grounded through the wiper 66, a circuit is established traceable from the grounded wiper 66, the contact to which the operator has brought the wiper 66, the waiting contact in connection 25 with this contact and pertaining to the wiper 64, the wiper 64 when engaging its waiting contact thus grounded, the lower intermediate armature switch of the relay 68 and its normal follow-up contact, to the 30 grounded battery 14. A locking circuit is 35 thereupon established for the relay 68 traceable from the grounded battery 14, the winding of relay 68, the lower intermediate armature switch of this relay, the alternate contact of this armature switch, the armature switch of relay 69 and its engaged contact, to ground. The two uppermost armature switches of relay 68 now engage their contacts which are connected each with 40 opposite talking sides of the link connector. The talking device 6 speaks the warning through its horn 70 into a transmitter 71 that is included in a local primary circuit whose primary coil is in inductive relation 45 with a secondary coil 72 having as its terminals the contacts of the two uppermost armature switches of the relay 68 that were previously connected with the talking strands of the employed link connector 50 whereby the voice currents impressed by the talking device 6 are impressed upon both telephone lines. The nature of the warning may be, for example, "Your time is up, you will be cutoff in a few seconds." 55 A motor 73 rotates disks 74 and 75 having angularly displaced contact fingers 76 and 77 which are non-simultaneously engaged by brushes 78, 79. When the finger 76 engages its brush 78 a circuit is established from 60 the grounded battery 14, through the finger 76, the brush 78, the lower armature switch of relay 80 and its normal follow-up contact, the winding of relay 80, the lowermost armature switch of relay 68 and its then 65 engaged contact, to ground. The locking

circuit is thereupon established for the relay 80 traceable from the grounded battery 14, the alternate contact of the lower armature switch of relay 80, said armature switch, the winding of relay 80, to the low- 70 ermost armature switch of relay 68. The upper armature switch of relay 80 establishes a circuit traceable from this armature switch, which is grounded, through the relay 69, the brush 79, the finger 77 when 75 engaging the brush, to the grounded battery 14. When the relay 69 is energized upon the engagement of the finger 77 with the brush 79, the locking circuit for the relay 80 is open so that the talking device 6 is removed from association with the connected lines whereby the connected subscribers may, during the added period of grace, pursue their conversation uninterrupted. The brush 65 engages its grounded waiting contact 80 a quarter of a minute after the brush 64 has engaged its grounded waiting contact, this being the period of grace during which the subscribers may talk, whereupon the circuit is traceable from the grounded 85 wiper 67, the contact to which the operator has brought the wiper 67, the waiting contact in connection with this contact and pertaining to the wiper 65, the wiper 65 when engaging its waiting contact thus grounded, 90 the winding of relay 51, to the grounded battery 14, whereupon this relay 51 is energized to attract its armature switches, the two lower armature switches thereupon leaving their contacts to break the talking sides 95 of the employed link connector. The uppermost armature switch of relay 51 opens the circuit of the motor magnet 61 to allow the wipers 64, 65 to remain at rest. 100 If the subscribers are through conversation they will restore their receivers upon their switch hooks causing the display of the signals 20 and 30 whereupon the operator will withdraw the plugs 18 and 25. The lower armature switch of the relay 29 will 105 now engage its normal contact to establish a circuit through the release magnet 81 and the previously closed off normal switch 82 whereby the wipers 64 and 65 are restored to normal. If the subscribers desire an extension of the period during which they may continue their conversation the calling subscriber will either inform the operator to this effect, or, as the invention is embodied, will deposit another token 56 to re- 110 energize the relay 22 momentarily to establish a circuit through the sluggishly operating relay 83 whose armature switch closes the circuit through the release magnet 81 to bring the wipers 64 and 65 to normal. The 115 wiper 65 in its normal position having opened the circuit of relay 51, the talking continuity of the employed link connector 120 is reestablished at the two lower armature switches of the relay 51 and a new period 125 130

during which the subscribers may speak is entered upon. If the information is conveyed to the operator that an extension of the period is desired the operator will 5 press the key 84 to energize the release magnet 81 to restore the wipers 64 and 65 whereupon connection is reestablished at the relay 51. The operator will then, by means of the device 8, simultaneously adjust the wipers 66, 67 to engage those waiting contacts that 10 will mark the termination of the extended period.

The drawings illustrate a manual exchange employing link connectors having 15 answering and connecting plugs for extending calling lines into connection with called lines but I do not limit myself to the manual extension of calling lines nor to the employment of operators for extending calling 20 lines into connection with called lines.

While I have herein shown and particularly described the preferred embodiment of my invention I do not wish to be limited to the precise details of construction and circuit arrangement shown as changes may 25 readily be made without departing from the spirit of the invention.

Having thus described my invention I claim as new and desire to secure by Letters Patent the following:—

1. A telephone exchange system including telephone lines extending from substations to an exchange; means for uniting lines in conversation; an announcer for informing 35 subscribers of the terminations of predetermined periods of service; timing mechanism for timely bringing the announcer into operative association with talking telephone lines; and operator controlled means for extending the periods of telephonic connection and placing said announcer in condition for re-operation at the terminations of the period extensions.

2. A telephone exchange system including 45 telephone lines extending from substations to an exchange; means for uniting lines in conversation; an announcer for informing subscribers of the terminations of predetermined periods of service; timing mechanism 50 for timely bringing the announcer into operative association with talking telephone lines; means for setting said timing mechanism into operation and jointly operated by equipment of calling and called subscribers 55 when telephonically connected; and operator controlled means for extending the periods of telephonic connection and placing said announcer in condition for re-operation at the terminations of the period extensions.

3. A telephone exchange system including 60 telephone lines extending from substations to an exchange; means for uniting lines in conversation; an announcer for informing 65 subscribers of the terminations of pre-

determined periods of service; timing mechanism for timely bringing the announcer into operative association with talking telephone lines; and subscriber controlled and operator controlled means for extending the periods 70 of telephonic connection and placing said announcer in condition for re-operation at the terminations of the period extensions.

4. A telephone exchange system including telephone lines extending from substations 75 to an exchange; means for uniting lines in conversation; an announcer for informing subscribers of the terminations of predetermined periods of service; timing mechanism for timely bringing the announcer into 80 operative association with talking telephone lines; means for setting said timing mechanism into operation and jointly operated by equipment of calling and called subscribers when telephonically connected; and subscriber controlled means for extending the periods of telephonic connection and placing said announcer in condition for re-operation 85 at the terminations of the period extensions.

5. A telephone exchange system including 90 telephone lines extending from substations to an exchange; means for uniting lines in conversation; an announcer for informing subscribers of the terminations of predetermined periods of service; timing mechanism 95 for timely bringing the announcer into operative association with talking telephone lines; and subscriber and operator controlled means for extending the periods of telephonic connection and placing said announcer in condition for re-operation at the 100 terminations of the period extensions.

6. A telephone exchange system including 105 telephone lines extending from substations to an exchange; means for uniting lines in conversation; an announcer for informing subscribers of the terminations of predetermined periods of service; timing mechanism 110 for timely bringing the announcer into operative association with talking telephone lines; means for setting said timing mechanism into operation and jointly operated by equipment of calling and called subscribers when telephonically connected; and subscriber and operator controlled means for 115 extending the periods of telephonic connection and placing said announcer in condition for re-operation at the terminations of the period extensions.

7. A telephone exchange system including 120 telephone lines extending from substations to an exchange; means for uniting lines in conversation; an announcer for informing subscribers of the terminations of predetermined periods of service; timing mechanism 125 for timely bringing the announcer into operative association with talking telephone lines; subscriber controlled means for extending the periods of telephonic connection and placing said announcer in condition for 130

re-operation at the terminations of the period extensions; and operator controlled means for variably extending the periods of telephonic connection and placing said announcer in condition for re-operation at the terminations of the period extensions.

8. A telephone exchange system including telephone lines extending from substations to an exchange; means for uniting lines in conversation; an announcer for informing subscribers of the terminations of predetermined periods of service; timing mechanism for timely bringing the announcer into operative association with talking telephone lines; means for setting said timing mechanism into operation and jointly operated by equipment of calling and called subscribers when telephonically connected; subscriber controlled means for extending the periods of telephonic connection and placing said announcer in condition for re-operation at the terminations of the period extensions; and operator controlled means for variably extending the periods of telephonic connection and placing said announcer in condition for re-operation at the terminations of the period extensions.

9. A telephone exchange system including telephone lines extending from substations to an exchange; means for uniting lines in conversation; an announcer for informing subscribers of the terminations of predetermined periods of service; timing mechanism for timely bringing the announcer into operative association with talking telephone lines; and operator controlled means for variably extending the periods of telephonic connection and placing said announcer in condition for re-operation at the terminations of the period extensions.

10. A telephone exchange system including telephone lines extending from substations to an exchange; means for uniting lines in conversation; an announcer for informing subscribers of the terminations of predetermined period of service; timing mechanism for timely bringing the announcer into operative association with talking telephone lines; means for setting said timing mechanism into operation and jointly operated by equipment of calling and called subscribers when telephonically connected; and operator controlled means for variably extending the periods of telephonic connection and placing said announcer in condition for re-operation at the terminations of the period extensions.

11. A telephone exchange system including telephone lines extending from substations to an exchange; means for uniting lines in conversation; cutoff mechanism for breaking telephonic connections between subscribers' stations at the conclusion of predetermined periods; timing mechanism for timely bringing the cutoff mechanism into operative

association with established circuits; and operator controlled means for delaying the operation of the cutoff mechanism to extend the periods of telephonic connections between stations.

12. A telephone exchange system including telephone lines extending from substations to an exchange; means for uniting lines in conversation; cutoff mechanism for breaking telephonic connections between subscribers' stations at the conclusion of predetermined periods; timing mechanism for timely bringing the cutoff mechanism into operative association with established circuits; and operator controlled means for variably delaying the operation of the cutoff mechanism to extend the periods of telephonic connections between stations.

13. A telephone exchange system including telephone lines extending from substations to an exchange; means for uniting lines in conversation; an announcer for informing subscribers of the terminations of predetermined periods of service; timing mechanism for timely bringing the announcer into operative association with talking telephone lines; and cutoff mechanism for breaking established connections brought into association with connected lines subsequently to the association of the announcer with connected lines.

14. A telephone exchange system including telephone lines extending from substations to an exchange; means for uniting lines in conversation; an announcer for informing subscribers of the terminations of predetermined periods of service; timing mechanism for timely bringing the announcer into operative association with talking telephone lines; means for setting said timing mechanism into operation and jointly operated by equipment of calling and called subscribers when telephonically connected; and cutoff mechanism for breaking established connections brought into association with connected lines subsequently to the association of the announcer with connected lines.

15. A telephone exchange system including telephone lines extending from substations to an exchange; means for uniting lines in conversation; an announcer for informing subscribers of the terminations of predetermined periods of service; timing mechanism for timely bringing the announcer into operative association with talking telephone lines; operator controlled means for extending the periods of telephonic connection and placing said announcer in condition for re-operation at the terminations of the period extension; and cutoff mechanism for breaking established connections brought into association with connected lines subsequently to the association of the announcer with connected lines.

16. A telephone exchange system including telephone lines extending from substations to an exchange; means for uniting lines in conversation; an announcer for informing subscribers of the terminations of predetermined periods of service; timing mechanism for timely bringing the announcer into operative association with talking telephone lines; means for setting said timing mechanism into operation and jointly operated by equipment of calling and called subscribers when telephonically connected; operator controlled means for extending the periods of telephonic connection and placing said announcer in condition for re-operation at the terminations of the period extensions; and cutoff mechanism for breaking established connections brought into association with connected lines subsequently to the association of the announcer with connected lines.

17. A telephone exchange system including telephone lines extending from substations to an exchange; means for uniting lines in conversation; an announcer for informing subscribers of the terminations of predetermined periods of service; timing mechanism for timely bringing the announcer into operative association with talking telephone lines; subscriber controlled means for extending the periods of telephonic connection and placing said announcer in condition for re-operation at the terminations of the period extensions; and cutoff mechanism for breaking established connections brought into association with connected lines subsequently to the association of the announcer with connected lines.

18. A telephone exchange system including telephone lines extending from substations to an exchange; means for uniting lines in conversation; an announcer for informing subscribers of the termination of predetermined periods of service; timing mechanism for timely bringing the announcer into operative association with talking telephone lines; means for setting said timing mechanism into operation and jointly operated by equipment of calling and called subscribers when telephonically connected; subscriber controlled means for extending the periods of telephonic connection and placing said announcer in condition for re-operation at the terminations of the period extensions; and cutoff mechanism for breaking established connections brought into association with connected lines subsequently to the association of the announcer with connected lines.

19. A telephone exchange system including telephone lines extending from substations to an exchange; means for uniting lines in conversation; an announcer for informing subscribers of the terminations of predetermined periods of service; timing

mechanism for timely bringing the announcer into operative association with talking telephone lines; subscriber and operator controlled means for extending the periods of telephonic connection and placing said announcer in condition for re-operation at the terminations of the period extensions; and cutoff mechanism for breaking established connections brought into association with connected lines subsequently to the association of the announcer with connected lines.

20. A telephone exchange system including telephone lines extending from substations to an exchange; means for uniting lines in conversation; an announcer for informing subscribers of the terminations of predetermined periods of service; timing mechanism for timely bringing the announcer into operative association with talking telephone lines; means for setting said timing mechanism into operation and jointly operated by equipment of calling and called subscribers when telephonically connected; subscriber and operator controlled means for extending the periods of telephonic connection and placing said announcer in condition for re-operation at the terminations of the period extensions; and cutoff mechanism for breaking established connections brought into association with connected lines subsequently to the association of the announcer with connected lines.

21. A telephone exchange system including telephone lines extending from substations to an exchange; means for uniting lines in conversation; an announcer for informing subscribers of the terminations of predetermined periods of service; timing mechanism for timely bringing the announcer into operative association with talking telephone lines; subscriber controlled means for extending the periods of telephonic connection and placing said announcer in condition for re-operation at the terminations of the period extensions; operator controlled means for variably extending the periods of telephonic connection and placing said announcer in condition for reoperation at the terminations of the period extensions; and cutoff mechanism for breaking established connections brought into association with connected lines subsequently to the association of the announcer with connected lines.

22. A telephone exchange system including telephone lines extending from substations to an exchange; means for uniting lines in conversation; an announcer for informing subscribers of the terminations of predetermined periods of service; timing mechanism for timely bringing the announcer into operative association with talking telephone lines; means for setting said timing mechanism into operation and

- jointly operated by equipment of calling and called subscribers when telephonically connected; subscriber controlled means for extending the periods of telephonic connection and placing said announcer in condition for re-operation at the terminations of the period extensions; operator controlled means for variably extending the periods of telephonic connection and placing said 50 announcer in condition for re-operation at the terminations of the period extensions; and cutoff mechanism for breaking established connections brought into association with connected lines subsequently to the association of the announcer with connected lines.
23. A telephone exchange system including telephone lines extending from substations to an exchange; means for uniting lines in conversation; an announcer for informing subscribers of the terminations of predetermined periods of service; timing mechanism for timely bringing the announcer into operative association with talking telephone lines; operator controlled means for variably extending the periods of telephonic connection and placing said announcer in condition for re-operation at the terminations of the period extensions; and cutoff mechanism for breaking established connections brought into association with connected lines subsequently to the association of the announcer with connected lines.
24. A telephone exchange system including telephone lines extending from substations to an exchange; means for uniting lines in conversation; an announcer for informing subscribers of the terminations of predetermined periods of service; timing mechanism for timely bringing the announcer into operative association with talking telephone lines; means for setting said timing mechanism into operation and jointly operated by equipment of calling and called subscribers when telephonically connected; operator controlled means for variably extending the periods of telephonic connection and placing said announcer in condition for re-operation at the terminations of the period extensions; and cutoff mechanism for breaking established connections brought into association with connected lines subsequently to the association of the announcer with connected lines.
25. A telephone exchange system including telephone lines extending from substations to an exchange; means for uniting lines in conversation; an announcer for informing subscribers of the terminations of predetermined periods of service; timing mechanism for timely bringing the announcer into operative association with talking telephone lines; operator controlled means for extending the periods of telephonic connection and placing said announcer in condition for re-operation at the terminations of the period extensions; cutoff mechanism for breaking established connections brought into association with connected lines subsequently to the association of the announcer with connected lines.
26. A telephone exchange system including telephone lines extending from substations to an exchange; means for uniting lines in conversation; an announcer for informing subscribers of the terminations of predetermined periods of service; timing mechanism for timely bringing the announcer into operative association with talking telephone lines; means for setting said timing mechanism into operation and jointly operated by equipment of calling and called subscribers when telephonically connected; operator controlled means for also delaying the operation of the cutoff mechanism to break telephonic connections subsequent to the renewed operations of the announcer.
27. A telephone exchange system including telephone lines extending from substations to an exchange; means for uniting lines in conversation; an announcer for informing subscribers of the terminations of predetermined periods of service; timing mechanism for timely bringing the announcer into operative association with talking telephone lines; subscriber controlled means for extending the periods of telephonic connection and placing said announcer in condition for re-operation at the terminations of the period extensions; cutoff mechanism for breaking established connections brought into association with connected lines subsequently to the association of the announcer with connected lines; and operator controlled means for also delaying the operation of the cutoff mechanism to break telephonic connections subsequent to the renewed operations of the announcer.
28. A telephone exchange system including telephone lines extending from substations to an exchange; means for uniting lines in conversation; an announcer for informing subscribers of the terminations of predetermined periods of service; timing mechanism for timely bringing the announcer into operative association with talk- 125

- ing telephone lines; means for setting said timing mechanism into operation and jointly operated by equipment of calling and called subscribers when telephonically connected; 5 subscriber controlled means for extending the periods of telephonic connection and placing said announcer in condition for re-operation at the terminations of the period extensions; cutoff mechanism for breaking established 70 connections brought into association with connected lines subsequently to the association of the announcer with connected lines; and operator controlled means for also delaying the operation of the cutoff mechanism to break telephonic connections subsequent to the renewed operations of the 75 announcer.
29. A telephone exchange system including telephone lines extending from substations to an exchange; means for uniting lines in conversation; an announcer for informing subscribers of the terminations of predetermined periods of service; timing mechanism for timely bringing the announcer into operative association with talking telephone lines; subscriber and operator controlled means for extending the periods of telephonic connection and placing said announcer in condition for re-operation 80 at the terminations of the period extensions; cutoff mechanism for breaking established connections brought into association with connected lines subsequently to the association of the announcer with connected lines.
30. A telephone exchange system including telephone lines extending from substations to an exchange; means for uniting lines in conversation; an announcer for informing subscribers of the terminations of predetermined periods of service; timing mechanism for timely bringing the announcer into operative association with talking telephone lines; subscriber and operator controlled means for extending the periods of telephonic connection and placing said announcer in condition for re-operation at the terminations of the period extensions; cutoff mechanism for breaking established connections brought into association with connected lines subsequently to the association of the announcer with connected lines; and operator controlled means for also delaying the operation of the cutoff mechanism to break telephonic connections subsequent to the renewed operations of the announcer. 85
31. A telephone exchange system including telephone lines extending from substations to an exchange; means for uniting lines in conversation; an announcer for informing subscribers of the terminations of predetermined periods of service; timing mechanism for timely bringing the announcer into operative association with talking telephone lines; operator controlled means for variably extending the periods of telephonic connection and placing said announcer in condition for re-operation at the terminations of the period extensions; and cutoff mechanism for breaking established connections brought into association with connected lines subsequently to the association of the announcer with connected lines.
32. A telephone exchange system including telephone lines extending from substations to an exchange; means for uniting lines in conversation; an announcer for informing subscribers of the terminations of predetermined periods of service; timing mechanism for timely bringing the announcer into operative association with talking telephone lines; means for setting said timing mechanism into operation and jointly operated by equipment of calling and called subscribers when telephonically connected; subscriber controlled means for extending the periods of telephonic connection and placing said announcer in condition for re-operation at the terminations of the period extensions; operator controlled means for variably extending the periods of telephonic connection and placing said announcer in condition for re-operation at the terminations of the period extensions; and cutoff mechanism for breaking established connections brought into association with connected lines subsequently to the association of the announcer with connected lines. 95
33. A telephone exchange system including telephone lines extending from substations to an exchange; means for uniting lines in conversation; an announcer for informing subscribers of the terminations of predetermined periods of service; timing mechanism for timely bringing the announcer into operative association with talking telephone lines; operator controlled means for variably extending the periods of telephonic connection and placing said announcer in condition for re-operation at the terminations of the period extensions; and cutoff mechanism for breaking established connections brought into association with connected lines subsequently to the association of the announcer with connected lines. 100
34. A telephone exchange system including telephone lines extending from substations to an exchange; means for uniting lines in conversation; an announcer for inform- 105

ing subscribers of the terminations of predetermined periods of service; timing mechanism for timely bringing the announcer into operative association with talking telephone lines; means for setting said timing mechanism into operation and jointly operated by equipment of calling and called subscribers when telephonically connected; operator controlled means for variably extending the 10 periods of telephonic connection and placing said announcer in condition for re-operation at the terminations of the period extensions; and cutoff mechanism for breaking established connections brought into association 15 with connected lines subsequently to the association of the announcer with connected lines.

35. A telephone exchange system including telephone lines extending from substations to an exchange; means for uniting lines in conversation; an announcer for informing subscribers of the terminations of predetermined periods of service; timing mechanism for timely bringing the announcer into operative association with telephone 40 lines while in telephonic connection; means for setting said timing mechanism into operation; and subscriber controlled means for extending the periods of telephonic connection.

45 for setting said timing mechanism into operation and jointly operated by equipment of calling and called subscribers when telephonically connected; and subscriber controlled means for extending the periods of telephonic connection.

36. A telephone exchange system including telephone lines extending from substations to an exchange; means for uniting lines 35 in conversation; an announcer for informing subscribers of the terminations of predetermined periods of service; timing mechanism for timely bringing the announcer into operative association with telephone 40 lines while in telephonic connection; means for setting said timing mechanism into operation; and subscriber controlled means for extending the periods of telephonic connection.

In witness whereof, I hereunto subscribe my name this thirty-first day of March, A. D. 1913.

MORTON L. JOHNSON.

Witnesses:

G. L. CRAGG,
E. L. WHITE.
